PRINTING PRESS FOLDER

Emory W. Worthington, Chicago, Ill., assignor to
 The Goss Printing Press Company, Chicago, Ill.,
 a corporation of Illinois

Application July 26, 1941, Serial No. 404,164

8 Claims. (Cl. 270—86)

This invention relates to printing presses and more particularly to an improved folding mechanism for high speed rotary printing presses which print on a running web of paper.

Objects and advantages of the invention will be set forth in part hereinafter and in part will be obvious herefrom, or may be learned by practice with the invention, the same being realized and attained by means of the instrumentalities and combinations pointed out in the appended 10 claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a side elevation of a printing press folding mechanism showing an illustrative embodiment of the present invention, certain parts being broken away for better understanding;

Fig. 2 is a side elevation on an enlarged scale of the former nose shown in Fig. 1, certain parts being broken away;

Fig. 3 is an exploded view in perspective of certain parts of the former mechanism shown in Fig. 1;

Fig. 4 is a horizontal sectional view of the former adjusting mechanism taken along line 4—4 of Fig. 1;

Fig. 5 is an elevation of the former adjusting and indicating mechanism taken along the line 5—5 of Fig. 4, certain parts being broken away;

Fig. 6 is a plan view of a printing press former and former rolls showing an illustrative embodiment of the present invention;

Fig. 7 is a fragmentary vertical section taken along the line 7—7 of Fig. 6;

Fig. 8 is a side elevation with certain parts broken away of a further illustrative embodiment of the invention; and

Fig. 9 is a side view on an enlarged scale of certain of the adjusting means shown in Fig. 6.

The present invention has for an object the provision of a novel and improved folding mechanism for printing presses printing on a running web to effect the first longitudinal fold of the printed web. A further object is to provide such an improved folding mechanism that will efficiently, accurately and surely effect the first longitudinal fold of the printed web, and which will so operate upon a single web or a number

of superposed webs simultaneously with equal efficiency and with the web moving at high speeds. Still another object is the provision of a folding mechanism which will accommodate either single webs or superposed multiple webs simultaneously, without tearing, wrinkling or mutilating the product in any way, and which may be easily, efficiently and certainly adjusted for various conditions of operation. The invention also provides independent adjustments for various members of a folding mechanism.

In accordance with the illustrative form of the present invention the folding mechanism of a printing press comprises a former and means for its angular adjustment with respect to the printing press. The nose of the former is formed of two members, the first of which is pivotally attached to the second, and the second is pivotally attached to the body of the former. Means are provided for the automatic angular adjustment of the two nose members with respect to each other by the pressure of the web or webs which are being folded at any given time, while means connected to the second nose member and under the control of the pressman are provided for the angular adjustment of the two nose members with respect to the body of the former. In accordance with one embodiment of the invention the adjusting means for the former with respect to the printing press and those for the nose members with respect to the body of the former are so constructed that either adjustment may be made without disturbing the setting of the other. Former rollers are provided adjacent the former nose to cooperate with the former in the longitudinal folding of the web or webs, and the ends of these rollers nearer the former nose may be laterally movably mounted and are adjustable by means under the control of the pressman for imparting simultaneous lateral opposite movement or independent lateral movement to the respective roller ends.

It will be understood that the foregoing general description and the following detailed description as well are exemplary and explanatory of the invention but are not restrictive thereof.

Referring now in detail to the illustrative embodiment of the invention as shown in the accompanying drawings, a printing press folding mechanism comprises a frame 10 having upwardly extending supporting members 11 upon which the main body portion 12 of the former is mounted for pivotal movement by means of its bracket 13 and pin 14, to receive the running web from the top of former roller 15, as shown

in Fig. 1. The body of the former 12 is finished at its lower apex with a cutaway surface 16 to receive the correspondingly shaped nose holder 17 which is fixed thereto as by screws 18. The intermediate member 19 forming a part of the former nose is pivotally mounted on the nose holder 17 by means of pins 20 extending through the two members, and the other and outermost member 21 of the former nose is in turn pivotally mounted in the slot 22 of the intermediate member and held as by a screw 23. The member 21 is spring pressed outwardly and against the surface of the web or webs by spring 24 secured to the under surface of the intermediate member 19.

Means are provided for adjusting the angular position of the former, and as illustratively embodied the folder frame 10 supports the integrally formed and upwardly extending bracket 25 in which the T shaped adjusting nut 26 is journalled for rotation. As shown in Fig. 4, the T-shaped adjusting nut 26 has a threaded hollow bore adapted to receive the cooperatively threaded end 27 of adjusting bar 28, which at its other end is pivotally attached as by bolt 29 to a bracket member 30 fixed to the under side of the main body portion 12 of the former. The annular internally threaded positioning and thrust bearing ring 31 is screwed upon the threaded inner end 32 of adjusting nut 26, and a jam nut 26' is provided on the threaded end 27 of the adjusting bar 28 to fix the adjusted position given to adjusting bolt 26. A dial 33 may be fixed to the bracket 25 adjacent the head of adjusting bolt 26 which carries the pointer 34 to indicate the particular angular adjustment given to the former.

Adjusting means are likewise provided for the angular positioning of the former nose members 19 and 21, and according to one embodiment an adjusting hand wheel 38 is fixed to one end of the adjusting rod 39 which is supportingly journalled for rotation between the gripping arms 40 of support bracket 41 which is mounted upon bar 28 and movably fixed thereto by a set screw 53. A collar 35 is fixed by a taper pin to rod 39 on the side of gripping arms 40 away from hand wheel 38 and serves, together with the axially extending annular portion 36 of the hand wheel, to prevent relative axial movement of rod 39 with respect to arms 40. The lever arm 42, bifurcated at either end and pivotally mounted by a bolt 44 on bracket 30, straddles the adjusting rod 39 to which it is anchored by a pintle 43, journalled in the lever and through which the rod is threaded, while link 46 is pivotally attached at the other end. Link 46 is pivotally attached at its other end to a bracket 47 fixed to the under side of the intermediate former nose member 19. A bolt 48 is inserted through the upper ends of the gripping arms 40 of the support bracket 41 and provided with a nut and arm 49 on its threaded end so that the pressman may lock the rod 39 against rotation. A dial 50 is mounted upon support bracket 41 and a pointer 51 on hand wheel 38 indicates thereon the angular position given to the nose members.

Novel and improved former rollers are provided to cooperate with the former in imparting a longitudinal fold to the web or webs being printed by the press, and according to a preferred embodiment the rollers 55, 56, are positioned adjacent the lower apex of the former on either side of the former nose. The ends of the rollers 55, 56 are journalled in the self-centering ball bearings 57, 58 respectively, and these bearings by means

of their respective integral enlarged base portions 59 are slidably mounted upon the frame 10 of the folder and between the L-shaped retaining and guiding members 60 mounted on the frame 10 and extending along said frame laterally of the axes of the former rollers. The oppositely threaded adjusting screws 61, 65 are tied together by the muff coupling 66, said coupling being fixed to screw 65 by pin 67 extending through the members and to screw 61 by a set screw 68. A plurality of holes 69 are provided about the periphery of coupling 66 into which a bar may be inserted for turning screw 65 independently of screw 61, set screw 68 being first disengaged. Screw 61 is mounted against axial movement on the frame 10 by bracket 62, and a hand wheel 64 is mounted on the end of the screw. The screws 61, 65 engage corresponding internal threads in the holes 63 of the bearings 58, 57 respectively, and it will be apparent that by turning the hand wheel 64 the ends of the rollers 55, 56 adjacent the former nose may be simultaneously moved equal distances either toward or away from each other, or, by disengaging set screw 68, the roller ends may be independently laterally adjusted. The other ends of the rollers 55, 56 may be mounted in self-centering ball bearings upon the frame 10 in any convenient manner.

With the illustrative embodiment of the invention shown and described it will be apparent that the folding mechanism for the printing press may be quickly and easily adjusted for the best operation under various printing conditions and with various sized products, and that the same is effected either while the press is stopped or during operation and is to an extent automatic but at the same time completely under the control of the pressman. By turning the adjusting nut 26 the angular relation of the whole former, including members 12, 19 and 21, with respect to the printing press may be varied and set, while the angular relation of the former nose members 19 and 21 with respect to the main body portion 12 of the former may be determined by turning the hand wheel 38, and this relation will not be affected by any adjustment made by the nut 26. The former nose member 21 is self adjusting under varying conditions by action of spring 24, and the distance between the ends of the rollers 55, 56 adjacent the former nose as well as their relative lateral positions may be determined by the pressman by the adjustments already described.

A modified form of the invention as applied to the former is shown in Fig. 3, and as there embodied the adjustment for the main body portion 12 of the former by means of adjusting nut 26 on bar 28 is as already described. One end of the adjusting rod 70 for the former nose member is journalled in a bracket 71 fixed to one of the upwardly extending members 11, while the other end is attached by universal joint 72 to the threaded link 73 which extends through a cooperatively threaded bore 74 of a bracket 75 attached to the main body portion 12 of the former. The other end of the link 73 is pivotally attached to a bracket 76 which is fixed to the intermediate former nose member 19, and the desired adjustment is effected by hand wheel 77 on rod 70.

The invention in its broader aspects is not limited to the specific mechanisms shown and described but departures may be made therefrom within the scope of the accompanying claims without departing from the principles of the invention and without sacrificing its chief advantages.

What I claim is:

1. In a printing press folder to effect a longitudinal fold in the web, a folder frame, a main body portion of the folder pivotally mounted on the frame, an intermediate former nose member pivotally mounted on the main body portion, a former nose end member pivotally mounted on the intermediate member, a spring attached to the intermediate member and engaging the end member to yieldingly press said end member outwardly toward the web, means connecting the frame and the main body portion for varying the angular relation therebetween, and separate means connecting the intermediate nose member and the first means for varying the angular relation between the intermediate nose member and the main body portion, whereby the angular relation between the main body portion and the frame may be varied without varying the angular relation between the main body portion and the intermediate nose member.
2. In a printing press folder to impart a longitudinal fold to the running web a substantially triangularly shaped former, a pair of spaced apart former rollers positioned to receive the web therebetween after it passes over the former and thereby fold the web longitudinally of its length, and means for independently moving the ends of said rollers adjacent the line of fold of the web toward or away from the line of fold.
3. A printing press folder to effect a longitudinal fold in the web comprising in combination a former having a main body portion, an intermediate nose member pivotally mounted thereon, and an end nose member pivotally mounted on the intermediate nose member and spring pressed outwardly toward the web, a pair of spaced apart former rollers one end of each positioned on either side of the former nose members, means for varying the angular relation of the intermediate and end nose members with respect to the main body portion of the former and means for moving the roller ends on either side of the former nose members toward or away from said nose members.
4. A printing press folder to effect a longitudinal fold in the web comprising in combination a folder frame, a former having a main body portion pivotally mounted on the frame, an intermediate nose member pivotally mounted on the main body portion, an end nose member pivotally mounted on the intermediate nose member, and spring means attached to the intermediate member and engaging the end nose member to yieldingly press said end member outwardly toward the web, means connecting the frame and the main body portion for varying the angular relation therebetween, means connecting the intermediate nose member and the main body portion for varying the angular relation therebetween, a pair of spaced apart former rollers one end of each positioned on either side of the former nose members, individual bearing means for the said roller ends slidably mounted on the frame, and means for sliding said bearing means toward or away from the nose members of the former.
5. In a printing press folder a former, a pair of former rollers an end of each being positioned on either side of the lower apex of the former, and means for independently moving the said former roller ends toward or away from the lower apex of the former.
6. In a printing press folder a former, a pair of former rollers an end of each being positioned on either side of the lower apex of the former, and selectively operable means for independently moving the former roller ends toward or away from the lower apex of the former and for simultaneously moving the former roller ends toward or away from the lower apex of the former.
7. In a printing press former, a main body portion pivotally mounted with respect to the printing press, a former nose pivotally mounted on the main body portion, means secured only with respect to the main body portion and nose for varying the angular relation between said main body portion and nose and maintaining the same in a desired angular relation, and other means for varying the angular relation of the main body portion and nose as an assembly with relation to the printing press.
8. In a printing press former, a main body portion pivotally mounted with respect to the printing press, a former nose portion pivotally mounted on the main body portion, a stationary member, adjusting means interconnecting one of said portions and the stationary member for varying the angular relation between the main body portion and the printing press, and other adjusting means interconnecting said portions with each other and unsecured to any stationary member for varying the angular relation between said portions and maintaining the same in a desired angular relationship whereby adjustment of the angular relation of the portions as an assembly with respect to the printing press may be effected without adjustment of said second adjusting means.

EMORY W. WORTHINGTON.
